CLAIM

I claim the ornamental design for a sports footwear sole, as shown and described.

DESCRIPTION

FIG. 1 is a bottom right perspective view of a sports footwear sole showing my new design;

FIG. 2 is a bottom left perspective view thereof;

FIG. 3 is a front elevational view thereof;

FIG. 4 is a rear elevational view thereof;

FIG. 5 is a bottom plan view thereof; and,

FIG. 6 is a side elevational view thereof.
